UNITED STATES PATENT OFFICE.

ROBERT R. TURNER, OF COLUMBUS, OHIO.

BOILER-FURNACE AND SMOKE-CONSUMER.

SPECIFICATION forming part of Letters Patent No. 518,870, dated April 24, 1894.

Application filed February 17, 1894. Serial No. 500,581. (No model.)

To all whom it may concern:

Be it known that I, ROBERT R. TURNER, a citizen of the United States, residing at Columbus, in the county of Franklin and State 5 of Ohio, have invented new and useful Improvements in Boiler-Furnaces and Smoke-Consumers, of which the following is a specification.

My invention relates to boiler-furnaces, and 10 the purpose thereof is to provide for the introduction of air at suitable points in the furnace in such manner that it shall be quickly heated to such a temperature that it will promote combustion and the complete consumption 15 of the gaseous products of the fuel.

It is a further purpose of my invention to provide a boiler-furnace in which air to support combustion shall be supplied from above and below, immediately in front of the fire-bridge, the air-currents being driven into the 20 fire-chamber over heated surfaces from which it derives a high temperature before mingling with the products of combustion.

The invention consists in the novel features 25 of construction and new combinations of parts hereinafter fully described and then definitely pointed out in the claims which form part of this specification.

To enable those skilled in the art to which 30 my said invention pertains to fully understand and to make, construct and use the same, I will now proceed to describe said invention in detail, reference being had, for this purpose, to the accompanying drawings, in which—

Figure 1 is a central vertical section of a 35 furnace constructed in accordance with my invention, the section being taken from front to rear. Fig. 2 is a front elevation, the air-inlets in the interior being shown in dotted lines.

In the said drawings the reference-numeral 1 indicates a structure of brick, or masonry, in which is the boiler-chamber, containing one or more boilers 2, which are usually of 45 the tubular type. The construction of these parts may be of any suitable or preferred form.

The reference-numeral 3 indicates the fire-chamber, which is inclosed within masonry 50 4, the top of which consists of an arch 5, the whole being arranged in front of the main structure 1. The fire-chamber 3 is provided

with a suitable grate 6, beneath which is the ash-pit 7.

Between the fire-chamber and the lower 55 portion of the boiler-chamber is the fire-bridge, or bridge-wall 8, behind which the floor 9 of the boiler-chamber, slopes gently upward to the pediment 10, which supports the boiler. The front face of the bridge-wall, which rises 60 above the fire-grate, is so constructed as to have an increasing projection toward the opposite, or front end of the fire-chamber, and I prefer to form this projecting portion by a series of angular courses 12, which project 65 successively one beyond the other and overhang the rearward end of the fire-chamber. The projecting portion may, if desired, comprise all that portion of the fire bridge which lies above the grate, but I prefer to project 70 the lower course 12 at a point about half-way between the grate and the top of the fire-bridge. The rearward portion of the arch 5 lies directly over the fire-bridge and is constructed with a downwardly projecting, or 75 hanging portion 13, which drops below the inner face of the main portion of the arch.

Between the top of the fire-bridge and the hanging portion 13 of the arch is a passage 80 14 for the products of combustion, through which they flow from the fire-chamber into the boiler-chamber.

In the fire-bridge I form one or more vertical air-conduits 15, which extend upward far enough to communicate with a series of substantially horizontal tuyeres 16, opening into the fire-chamber immediately beneath the lower projection 12 of the fire-bridge, said tuyeres being formed at suitably frequent intervals from one end of the fire-bridge to 90 the other, or nearly so.

In the upper portion of the arch 5 is placed a series of pipes, or conduits 17, of any suitable kind, opening at their outer ends through the end wall of the fire-chamber. At their 95 opposite extremities these pipes, or conduits, open into a series of vertical tuyeres 18, which discharge directly in front of the hanging portion 13 of the arch, the air being caused to flow over the vertical face thereof before 100 it can enter the passage 14. In a similar manner, the air discharged from the tuyeres 16 is driven over the series of projections 12 before it mingles with the heated gases and products

of combustion flowing through the passage 14. In both cases, the entering air is not only exposed to the fierce heat of the fire-chamber but is also brought into intimate contact with the intensely heated surfaces over which it is compelled to flow, whereby its temperature is raised to a high degree, so that it will promote combustion and largely increase the available heat, besides effecting a complete consumption of the products of combustion within the boiler-chamber, thus securing an important economy in fuel-consumption, proportionately to the steam-pressure produced. It is evident that I may employ a natural draft, or a forced draft, to supply the tuyeres 15 and 18, though the drawings of this application show the former, only. The various means for creating a forced draft are so well known however, that I do not regard it as necessary that any specific means for such purpose be illustrated.

I prefer to arch, or curve, the top of the fire-bridge 8, as shown in dotted lines in Fig. 2, in order to assimilate its form to that of the overhanging arch 13 and render the passage 14 of equal dimensions throughout, or from side to side. I may, also, form the air-supply openings entirely within the masonry, or fire-brick structure, and avoid the use of pipes entirely. By this construction of furnace I obtain a complete consumption of the smoke, so that the furnace may properly be called smokeless.

What I claim is—

- 35 1. In a boiler furnace, a bridge wall having the upper end of its front portion provided with a series of forwardly projecting angular courses successively extending one beyond another, and a series of tuyeres formed in the body of the bridge wall and discharging horizontally directly beneath the said angular courses, substantially as described.
- 40 2. In a boiler furnace, a bridge wall having the upper end of its front part provided with a series of projecting angular courses successively extending one beyond another, tuyeres formed in the body of the bridge wall and discharging horizontally directly beneath the said angular courses, and an arch forming the top wall of the fire-chamber and having the rear portion overhanging the bridge wall projected downwardly below the inner face of the remaining portion and formed

with a series of tuyeres which discharge downwardly in front of the front face of said 55 downwardly projected end of the arch, substantially as described.

3. In a boiler-furnace, a fire-chamber separated from the boiler-chamber by a fire-bridge having a portion of its wall lying above the 60 grate projected toward the outer end of the fire-chamber, the top of the latter being provided with a downwardly projecting portion which overhangs the fire-bridge and drops below the remaining part of the top wall, 65 said fire-bridge and top being provided with tuyeres discharging beneath the projection of the former and in front of the dropped portion of the latter, substantially as described.

4. In a boiler-furnace, the combination with 70 a fire-bridge having a series of tuyeres discharging, beneath a projecting portion of the wall, overhanging the rear end of the fire-chamber, of an arched top to the fire-chamber, having a series of tuyeres discharging 75 downwardly in front of a downwardly projected portion which overhangs the fire-bridge, substantially as described.

5. In a boiler-furnace, a fire-bridge having a series of angular projecting courses which 80 extend successively and overhang the rear end of the fire-chamber, a series of tuyeres discharging beneath the lower angular course, an arched top wall having that portion which overhangs the fire-bridge dropped below the 85 remaining portion, and a series of tuyeres discharging downward in front of said dropped portion, substantially as described.

6. In a boiler furnace an upwardly arched, or convex fire-bridge, having a series of successively projecting angular courses which overhang the rear end of the fire-chamber, a series of tuyeres discharging air beneath the lower angular course, an arched top wall having that concave portion which overhangs the 95 curved fire-bridge dropped below the remaining portion and a series of tuyeres discharging in front of said dropped, concave part, substantially as described.

In testimony whereof I have hereunto set 100 my hand and affixed my seal in presence of two subscribing witnesses.

ROBERT R. TURNER. [L. S.]
